UNITED STATES PATENT OFFICE.

DAVID E. HUGHES, OF SAN PEDRO, CALIFORNIA, DEDICATED TO THE PUBLIC, BY
ASSIGNMENT.

DREDGE CUTTER.

Application filed November 9, 1921. Serial No. 514,101.

(FILED UNDER THE ACT OF MARCH 3, 1883, 22 STAT. L., 625.)

To all whom it may concern:

Be it known that I, DAVID E. HUGHES, Engineer Corps, United States Army, and resident of San Pedro, in the county of Los Angeles and State of California, have invented a new and useful Improvement in Dredge Cutters, of which the following description, in conjunction with the accompanying drawings, is a specification.

10 The invention described herein may be used by the Government, or any of its officers or employees in prosecution of work for the Government, or by any other person in the United States, without payment of any royalty thereon.

This invention relates to suction dredging machines, more particularly it is directed to an improved type of cutter especially efficacious for cutting into hard pan or other 20 relatively hard material.

One of the principal objects of this invention is to provide a simple and efficient cutter which will enhance the material output and afford smoother and easier running of the cutter engine when employed in connection with dredges operating in rivers and harbors having beds of exceptionally hard material.

Another object of this invention is to effect an improved cutter designed to prevent any time interval between successive engagements of the blades with the material being dredged whereby excessive variations in torque and the resulting vibrations or 30 jerks so highly detrimental to the dredge assembly are eliminated.

Other objects of this invention are to furnish a cutter having facilities for materially decreasing the time required for dredging 40 material of the character designated and which will function to reduce the depth of the valueless V shaped dredging grooves.

With these and other objects in view this invention consists in certain novel details 45 of construction, combination and arrangement of the parts to be more particularly hereinafter set forth and claimed.

Briefly stated, this invention consists of a 50 cutter frame equipped with suitable cutter blades, the frame being in the form of a

conical frustum and involving a ring adapted to encircle the suction pipe, a nose coaxial with the ring and connected to the latter by a series of dextrorsally spiraled serrated vanes and cutting blades attached to 55 the inner surfaces of the vanes.

Referring more particularly to the accompanying drawings in which corresponding parts are indicated by similar reference characters:

Fig. 1. Is a side elevation of this improved cutter.

Fig. 2. Is an end view thereof, and

Fig. 3. Is a side elevation of the cutter frame, without the blades.

When engaged in dredging certain rivers and harbors having beds of exceptionally hard material it was found:

(a) The power of the cutter engine was materially limited and could not be increased without jeopardizing the cutter gear and shaft.

(b) The material dredged was not only difficult to cut but when worked became quite sticky.

(c) Cutters of various designs, although good in other materials, would frequently "ball up" in this hard pan.

(d) The advance had to be small and the cutting so shallow that but one blade could be engaged at a time thus producing the greatest variation in torque and excessive vibrations or jerkings damaging to ladder, gearing, cutter engine, steam pipes and 80 spuds.

To produce a cutter capable of meeting the preceding conditions it was deemed advisable:

(a) To lessen the torque by effecting a reduction of the cutter radius.

(b) To confine the reductions to the forward end of the cutter inasmuch as its rear end had to encircle the suction pipe. This limitation, however, proved advantageous as it placed the shortest radius where cutting 95 would be hardest and where it would serve to reduce the depth of the valueless V shaped grooves dredged below the required channel depth.

(c) To equalize the torque as much as 100

practicable by twisting or spiraling the cutters to a degree greater than customary in constructions of this character.

(d) To serrate the cutter blades for the purpose of avoiding backward and forward movement of the dredge produced by excessive spiraling of smooth continuous blades and to impart a moderate twist to the cutting edge of each tooth best suited to the material dredged.

The design resulting from the preceding theories when in use demonstrates their accuracy, as it gave freedom from vibrations and jerkings of the dredge smooth and easy running of the cutter engine, and an increased output of approximately twenty per cent.

In the illustrated embodiment characterizing this invention there is shown a cutter frame (1), cast in the form of a conical frustum and comprising a rear ring or rim (2), a hub (3) coaxially spaced from the ring and formed with a plurality of radially extended spokes (4) having downwardly and rearwardly turned extremities, integral with the upper ends of conically spiraled blade supporting vanes (5) the lower extremities of which are cast integral with ring (2) as clearly shown in Figures 1 and 3 of the drawings.

Vanes (5) are dextrorsally spiraled and serrated along their upper edges as at (6) while their inner surfaces are formed with a longitudinal seat (7) for a purpose herein-after to appear.

A serrated cutter blade (8) shaped to conform to the curvature of the vanes (5) is bolted or otherwise secured to the inner surface of each vane with its lower edge abutting seat (7). The rear extremities of the cutter blades are projected into plane of ring (2) and sufficiently from the ends of vanes (5), which are likewise extended, to excavate a clearance for hub and spokes. Cutter blades (8), although shown in single pieces, are preferably constructed in two or more sections, as the forward teeth require renewal more frequently than any of the others.

A cutter constructed as outlined with its succession of teeth may be favorably compared to a gang plow, in that each tooth makes its furrow in advance of the next, the hard pan or like material being broken or torn from its bed rather than cut as in the case of cutters utilizing continuous blades, while the multiplicity of teeth materially increase the number of points at which the bed is engaged during each revolution of the cutter head, thus avoiding backward and forward movement of the dredge.

To obtain this plow-like effect it is essential to have the foremost teeth of each gang at the rear of the cutter head, that is to say the spiral of the blades is such that their

rear travels circumferentially in advance of their forward extremities.

By this arrangement each furrow has a free or loosened side, which facilitates breaking or tearing the bed and renders cutting much easier than would be the case if the foremost teeth were located at the front of the cutter, in which event the cutter would have to penetrate material firmly bound on both sides.

In conclusion it may be stated when initially placed in service this cutter evidences its superiority by affording smoother and easier running of the engine, eliminating vibration and jerking of the dredge and maintaining its position in the cut exceptionally well and only reacting against the spud when the forward or front teeth and their extensions require renewal or repair.

Although, in the foregoing, certain elements have been referred to, as best adapted to perform the functions allotted to them, it is to be understood that various minor changes with respect to the formation of the blades and means of casting the cutter frame, may be resorted to within the scope of the appended claims without departing from or sacrificing any of the principles of this invention.

Having defined my invention, what I claim is new and wish to secure by Letters Patent is:

1. A cutter comprising a cutter frame provided with spiral blade supporting vanes, a cutting blade secured to the inner surface of each of said vanes and conforming in curvature to the latter, the spiral of the blade being such that its rear travels circumferentially in advance of its forward extremity.

2. A cutter comprising a cutter frame involving a ring, a hub spaced from the ring and formed with radially extending spokes, blade supporting vanes spirally arranged between and interconnecting the ring and extremities of the spokes and a similarly spiraled cutting blade secured to each of said vanes, the spiral of the cutting blade being such that its rear travels circumferentially in advance of its forward extremity.

3. A cutter frame involving a ring, a hub spaced from the ring and formed with radially extending spokes, blade supporting vanes spirally arranged between and interconnecting the ring and extremities of the spokes and a similarly spiraled cutting blade secured to and overlying the inner surface of each of said vanes, the spiral of the cutting blade being such that its rear travels circumferentially in advance of its forward extremity.

4. A cutter frame involving a ring, a hub spaced from the ring and formed with radially extending spokes, blade supporting vanes spirally arranged between and inter-

connecting the ring and extremities of the spokes, and a similarly spiraled serrated cutting blade secured to and overlying the surface of each of the vanes, the spiral of each cutting blade being such that its rear travels circumferentially in advance of its forward extremity.

5. A cutter comprising in combination a conical frustum-shaped frame and a plurality of cutting elements supported by the frame, the cutting elements being spiraled so that their rear travels circumferentially in advance of their forward extremities.

DAVID E. HUGHES.
